Primary Examiner — Joseph Kukella

Assistant Examiner — Arva P Adams

(57) **CLAIM**

The ornamental design for a bottle, as shown and described.

DESCRIPTION

FIG. 1 is a front, left, and top perspective view of a bottle, showing my new design;

FIG. 2 is a rear, right, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof; and,

FIG. 9 is a detailed view taken from encircled portion labeled “FIG. 9” in FIG. 2.

The dot-dash broken lines in FIGS. 2 and 9 denote the boundaries of the detail areas and form no part of the claimed design. The even dash broken lines in the drawings are portions of the bottle that form no part of the claimed design.

1 Claim, 9 Drawing Sheets
